UNITED STATES PATENT OFFICE

STEPHEN B. STAFFORD, OF OXFORD, AND JOHN WARREN VEDDER, OF WORCESTER, MASSACHUSETTS, ASSIGNORS TO RICE, BARTON & FALES, INCORPORATED, OF WORCESTER, MASSACHUSETTS, A CORPORATION OF MASSACHUSETTS

PAPER DRIER

Application filed July 23, 1928. Serial No. 294,621.

This invention relates to that type of driers used to receive a web of paper in a wet condition and dry it. The principal objects of the invention are to provide a continuous machine for this purpose which shall combine the advantages of the so-called slat-driers, the so-called "air" drier and the so-called "festoon" drier and retain the cockle in the paper; to provide a machine which will dry a large amount of paper and occupy a small space; to provide a construction in which the strain on the slatted drums employed will be materially reduced on account of the way in which they are mounted; to provide a machine which will distribute the heated air or other heating medium with sufficient circulation without the employment of fans or other means for assisting in its distribution; to provide an arrangement of the slatted drums, one over the other, for the purpose of reducing the ground space necessary for the thorough drying of the web before it leaves the drier; and to provide a driving means by which one series of drums will be driven directly and accurately at the same speed and for driving the other series in a similar manner therefrom.

Other objects and advantages of the invention will appear hereinafter.

Reference is to be had to the accompanying drawings in which

Fig. 1 is a side view of a drying machine constructed in accordance with this invention with some of the parts shown diagrammatically;

Fig. 2 is a sectional view on the line 2—2 of Fig. 1, showing one of the drums in elevation and the other in section;

Fig. 3 is a sectional view on the line 3—3 of Fig. 1, and

Fig. 4 is a sectional view on the line 4—4 of Fig. 1.

There are several methods of drying paper in wet condition, depending somewhat on the type of paper which is being made. Some of them involve a second drying after sizing or otherwise treated. Among the devices for this purpose are the so-called "slat" driers, "air" driers and the "festoon" driers. This

invention is designed to combine their advantages and at the same time to secure the advantages of their systems.

Referring to the drawings it will be seen that the web of paper W is drawn over a carrying roll 11 into the drying machine which comprises a frame 10. The paper passes upwardly, in this case, to a slat drum 12 around more than the half of the surface of which it passes on account of the particular arrangement of this drum relative to a lower drum 12. The paper passes in the same way over and under a series of upper and lower drums, shown in this case as divided into two series of lower drums and two series of upper drums, and finally it comes out under the last of the lower drums 12 and over a carrying roll 13 where it is delivered in a dried condition. The lower and upper drums are separated a considerable distance to allow for adequate drying.

For the driving of these drums in the two series there is a driving shaft 14 in each of the lower series on which is a gear 15. This gear meshes with two gears 16 on the ends of two of the drums 12, thereby driving both of these drums in the same direction. It will be understood that the invention is not limited to two series of three drums each at the bottom and top as shown, but, however many of these drums there are, they are all provided with the gear 16 and driven by gears 15.

At some point along the series, as for example a shaft 17 on which one of the gears 15 is mounted, is a sprocket wheel 18 on the same shaft. This sprocket wheel by means of a chain 19 drives a sprocket 20 on one of the drums 12 of the upper series. This particular gear 16 drives two gears 15 like those mentioned below located on short shafts which in turn drive the gears 16 on the drums 12 on either side.

This system can be extended in accordance with this invention throughout a greater number than that shown if desired. In this case both of the series are driven in the same way from two shafts 14, they being shown as exactly alike. This results in the driving of all the drums at the same surface

speed as they are positively connected with each other.

It will be seen that in the arrangement of the drums, those at the top are located directly over those at the bottom. On account of the way in which the web is carried over and under the drums, it will be seen that it passes backwardly from each upper drum to the lower drum under which it passes and that, for that reason, the web passes more than half way around each upper drum.

A corresponding arrangement is provided at the bottom so that the same result is secured there. This is advisable because these are open drums, as will appear, and this enables the heating medium to operate conveniently on a comparatively long length of paper as it passes around each drum.

20 The heat that emerges through the drum at the bottom of the upper drums and the tops of the lower drums escapes slowly because it is confined between the converging strands of the web and heating takes place even after the web has left each drum and before it reaches it. The heat eventually escapes at the top and sides but there is no place where a current of moisture-laden heated air will encounter the edges of the web and leave them 25 more moist than the center.

Each of the drums is shown as mounted on a stationary shaft 21 which is hollow and is connected with a source of heating medium, as hot air, which enters through a pipe 22 from a suitable source of supply. The other end of the shaft is closed by a plug 23 and, as stated, the pipes are fixed in brackets 24 on the frame 10. On these pipes are located anti-friction bearings 25 shown as of the ball 30 type and carrying the hubs 26 at the opposite ends of each drum. Each drum is provided with a spider or spokes 27 extending from the hubs and having sockets 28 for receiving slats 29. These slats extend the length of the drum 35 and are spaced apart so that the web of paper runs on the slats alone. The rest of the invention can be used with a drum keyed to a revolving shaft.

30 The gears 16 on these drums are located at one end of, and integral with, the casting 50 preferably which comprises the hub, spokes and sockets. Where the sprocket wheels 18 and 20 are used, they are fastened to the hub at one end.

55 It will be seen that this furnishes a positive drive which will secure uniform speed of all the drums, provides an arrangement of the drums which will efficiently dry the paper and occupy a comparatively small space for 60 its drying capacity, and that the drums, being mounted on stationary tubes by means of anti-friction bearings, are not badly strained by the passage of the paper over them or the driving means, although one end of each 65 drum is connected with the driving end by a

skeleton frame-work. The advantages of the ordinary air drier are all retained and also the advantages of the so-called "air" or "festoon" systems of drying are employed in the same machine.

70 Although we have illustrated and described only a single form of the invention, we are aware of the fact that modifications can be made therein by any person skilled in the art without departing from the scope of the invention as expressed in the claims.

75 Therefore, we do not wish to be limited to all the details of construction herein shown and described, but what we do claim is:

1. In a drier for paper coming directly 80 from a paper machine, the combination of two series of slatted heated drums for receiving the paper continuously, one series being spaced materially above the drums of the other series, a gear on each drum, shafts located between each two drums and each having a gear thereon meshing with the gears on the two adjacent drums for rotating them all in the same direction, one of said shafts in one series having a sprocket wheel thereon and 85 one of the drums in the other series having a sprocket wheel and a chain connecting said sprocket wheels whereby both series of drums 90 will be driven simultaneously.

2. In a drier for paper coming directly 95 from a paper machine, the combination of two series of drums for receiving the paper continuously, one series being spaced above the other series, a gear on each drum, shafts located between each two drums and each 100 having a gear thereon meshing with the gears on the two adjacent drums for rotating them all in the same direction, means for driving one series from the other, a stationary hollow shaft provided with perforations therein on 105 which each drum is mounted to rotate and means for introducing a heating medium into each of said shafts.

3. In a drier for paper coming directly 110 from a paper machine, the combination of two series of slatted heated drums for receiving the paper continuously, one series being spaced materially from the drums of the other series, a gear on each drum of one series, shafts located between each two drums 115 and each having a gear thereon meshing with the gears on the two adjacent drums for rotating them all in the same direction.

120 In testimony whereof we have hereunto affixed our signatures.

STEPHEN B. STAFFORD.
JOHN WARREN VEDDER.
